STANLEY BROWN, OF GARDEN CITY, NEW YORK, ASSIGNOR TO THE GRISCOM-RUSSELL COMPANY, OF NEW YORK, N. Y., A CORPORATION OF DELAWARE

SCALE SHEDDING HEAT TRANSFER APPARATUS

Application filed July 15, 1930. Serial No. 466,013.

The present invention relates to heat exchangers such as evaporators, condensers and feed water heaters wherein tubes are employed as agencies of heat transmission from one fluid medium to another. The invention more especially relates to heat exchangers in which the tubes are partially or wholly covered with liquid containing scale-forming impurities which during the operation of the apparatus tend to form scaly deposits upon the surfaces of the tubes.

Thus, for example, in the case of an evaporator, it is customary to derive the heat for causing the evaporation of the liquid from steam which is admitted to the heat transferring tubes or coils arranged within a suitable shell containing the liquid to be evaporated. The raw water which is fed to the evaporator usually contains various solids or other materials which tend to form scale on the evaporator tubes. Moreover, in certain types of condensers, particularly those used in oil refining work, where very frequently the cooling water is contaminated with scale-forming impurities, the matter of scale removal is also a problem. In such condensers the oil is usually sent through the interiors of the tubes, and the cooling water over the exteriors of the tubes. The scale collects on the surfaces of the tubes and some provision has to be made for its removal.

Various expedients have been employed to provide for this scale removal, one of the most usual and most effective arrangements being the bowed tube construction in which the tubes are very nearly straight and the forces of expansion and contraction caused by temperature changes produce a warping movement or bowing of the tubes which removes the scaly deposits on the tubes. In the usual arrangement of the bowed tube construction, however, tube sheets are employed at both ends of the tube bundle, and this is undesirable under certain conditions.

The principal object of the present invention is to provide an apparatus in which the tubes are of such shape and are so mounted that a scale-shedding or scale-removing movement of the tubes is produced under changes in temperature without the neces-

sity of employing headers at both ends of the tube bundle.

Another object of the invention is to provide a heat exchanger having tubes of such construction that an effective self-scaling movement thereof is produced under variations in temperature and at the same time do away with the necessity for stress-carrying members extending throughout the length of the tube bundle.

A further object of the invention is to provide a heat exchanger of improved construction and having adequate scale-removing characteristics.

A still further object of the invention is to provide a heat exchanger having its tubes so constructed that changes in both temperature and pressure produce an effective scale-shedding movement thereof.

Having the above objects in view, the invention will now be described in connection with the accompanying drawings in which

Fig. 1 is a sectional elevational view illustrating an apparatus embodying my invention.

Fig. 2 is a similar view of a modified form of apparatus.

Fig. 3 is a view looking toward the right hand end of Fig. 1 with the cover of the apparatus removed.

Fig. 4 is a diagrammatic view of a single heat exchanger element of the kind shown in Figs. 1 and 2.

Fig. 5 is a diagrammatic view of a modified form of heat exchanger element.

Fig. 6 is a diagrammatic view showing another modification of the heat exchanger element; and

Fig. 7 is a view showing the cross-section of the curved portion of the element of Fig. 6.

The principle of operation of my invention by means of which the scale-shedding movement of the heat exchanger tubes is produced will be easily understood by referring first to Figs. 4, 5 and 6 of the drawings.

In Fig. 4 the heat exchanger tube 10 which is of copper, brass, steel or other suitable metal having a relatively high coefficient of expansion, is made with two slender legs 11 and 12 of unequal length jointed together at

one end by a curved portion 13. At their opposite ends the tubes are secured in manifolds 14 and 15 or other mountings which are rigidly fixed in position in any suitable manner. The legs 11 and 12 may be perfectly straight, or nearly straight, or they may be slightly bowed. Even if slightly bowed, however, they are straight in comparison to the curved portion 13.

- 5 10 Steam or other heating or cooling medium is delivered to and discharged from the tube 10 by means of these manifolds, the medium preferably entering through manifold 14 and leaving by manifold 15. The leg 11 is shorter than leg 12 as shown, and consequently when the temperature of the tube increases, as for example when steam is sent through a cold tube, the expansion of the leg 12 is greater than that of leg 11. Consequently 15 the tube moves upwardly and assumes a new position approximately as indicated by the dotted lines in Fig. 4.
- 15 20 Referring now to Fig. 5 of the accompanying drawings, the heat exchanger tube 16 here illustrated is of serpentine form with a plurality of straight portions joined together by return bends 17, 18 and 19. The construction of the tube is such that no two consecutive straight portions are of equal length, and the uppermost straight portion is connected to a supply manifold 14a and the lowermost straight portion to a discharge manifold 15a.

25 30 This serpentine form of heat exchanger element, when heated by the passage of steam therethrough, behaves in a manner quite similar to the tube 10. Because of the compound formation of this tube, the movement is a compound movement and the tube 16 as a 35 whole assumes a position about as shown in the dotted lines.

35 40 The heat exchanger elements previously referred to are constructed of tubing which is circular in cross-section throughout its length. In Figs. 6 and 7 there is illustrated a form of heat exchanger element 10b which is similar in general proportions to tube 10. In tube 10b the straight portions 11b and 12b are of circular cross-section, but the curved 45 50 portion or bend 13b, however, is of flattened cross-section.

45 55 With an increase in temperature and pressure there is a cooperative warping brought about by the difference of elongation of the straight portions 11b and 12b and an effort on the part of the curved portion 13b to increase its radius or straighten out. This cooperative action brings about a general deformation throughout the entire tube.

60 65 I make use of the motion imparted to tubes constructed in this manner and caused by the normal variation in temperature which ordinarily takes place, or which can readily be made to take place in the operation of many 70 75 types of heat exchangers, such for example

as evaporators, condensers, feed water heaters, and the like, in preventing the formation of scale on the surfaces of the tubes, and in causing the tubes to shed the scale or exfoliate the same after it has once formed.

70

In Figs. 1, 2 and 3 I have shown the manner in which the tubular heat exchanging elements of the type illustrated in Figs. 3, 4 and 6 can be embodied in commercial forms of evaporators. In Fig. 1 a plurality of scale-shedding tubes 10 are arranged in the form of a tube bundle 20 mounted within the containing shell 21. Steam is supplied to the tubes 10 through a suitable inlet opening 22, and after being condensed in its passage 75 80 through the tubes 10 is discharged at the outlet 23 provided for this purpose.

The vapor generated in the evaporator shell rises into the dome 24 and leaves the evaporator through the opening 26. An inlet for raw water entering the evaporator shell is provided at 28. The upper short legs of the tubes 10 are secured in a tube sheet 29 and the lower long legs in a tube sheet 30 and these tube sheets are disposed in different vertical planes 90 at a distance from one another, and are held in fixed position in a manner which will presently be described. The tubes in the tube bundle 20 are hence supported in the same way as described in connection with Fig. 4 95 so that the scale-shedding movement takes place when the tubes are subjected to change in temperature.

95 100 Preferably the tube bundle 20 is built in sections, and for this purpose a plurality of sectional headers are employed as illustrated in Fig. 3. Each of these headers 31 is a long narrow casting removably secured to the steam inlet manifold 32 by means of bolts 33 and 34 and to a drain manifold 35 by means 105 of bolts 36.

105 110 Inlet manifold 32 extends horizontally across the upper portion of the evaporator shell and is placed in communication with the inlet 22 by means of a conduit 37. Drain manifold 35 extends parallel to manifold 32 across the bottom part of the evaporator shell and is connected with the outlet 23 by a connection 38 which joins the drain manifold at its center.

110 115 Referring particularly to Fig. 1, each of the headers 31 has in its upper part a distributing chamber 39 and in its lower part a collecting chamber 40, these chambers being separated by a partition wall 41. The distributing chamber 39 is relatively deep and extends for a considerable distance to the rear of the front face 42 of the header while collecting chamber 40 is shallow. Tube sheet 29 forms the rear wall of distributing chamber 120 125 39 and tube sheet 30 forms the rear wall of collecting chamber 40.

120 125 The steam entering inlet 22 passes through conduit 37 and is delivered to each of the several headers 31 of manifold 32. Each of the 130

headers 31 therefore receives its quota of steam from the manifold and the steam entering chamber 39 is distributed to the various tubes of the tube bundle. In passing through the tubes the steam is condensed and the hot condensate is discharged into collecting chamber 40 from which it passes to connection 38 and outlet 23.

The ends of the tubes 10 are preferably secured in the tube sheets 29 and 30 by means of an expanding tool in the ordinary manner, and for the purpose of affording access to the tube ends, holes are made in the front face 42 of each header in register with the respective tube ends. A tool for affixing the tubes to the tube sheet may be inserted through these holes and likewise accessibility is provided for cleaning the interior of the tubes. Each hole is tapped and provided with a suitable plug 43 to render the chamber fluid-tight during the operation of the apparatus. Preferably each of the headers 31 supports two vertical rows of heating tubes arranged in staggered relation as shown in Fig. 3.

In the modified form of construction shown in Fig. 2, the arrangement of the various parts is identical with that just described in connection with Figs. 1 and 3, except that the staggering of the ends of the U-shaped heating tubes 10 is secured in a different way. Thus the evaporator shell, the raw water delivery, the vapor dome and vapor discharge are identical with the corresponding elements of Figs. 1 and 3, also the steam inlet and the outlet for the drains from the tube bundle.

In order to provide for supporting the ends of the long legs of the heating tubes in staggered relation to the ends of the short legs, however, a somewhat different construction is employed. For this purpose the faces of the steam inlet manifold 32' and the drain discharge manifold 35' instead of being in a vertical plane, are arranged at an angle to the vertical, and the sectional headers 31' instead of being at right angles to the axes of the tubes 10' are oblique thereto. The headers 31' are, however, removably bolted in place as previously described in connection with Figs. 1 and 3.

The tubes 10 and 10' are preferably of small bore which not only gives them a large surface in proportion to their cross-sectional area, but at the same time provides a suitable degree of flexibility throughout their length.

Although it is preferable to mount the unequal length U-tube heating elements of Fig. 4 horizontally, this is not a necessary requirement and if desired they may be arranged vertically but in this event the headers should be placed at the bottom.

In the operation of the evaporators illustrated in Figs. 1 to 3 inclusive, the water level is preferably maintained as indicated by the dotted lines in Figs. 1 and 2 so as to just

cover the tube bundles and also at about five-eighths to about two-thirds of the height of the shell so as to leave an adequate vapor space above the tube bundle.

The tubes are sealed by causing a quick expansion or contraction of the tubes. This may be accomplished by filling the evaporator shell with cold water and admitting steam to the tubes, or with hot water still in the shell the tubes may be flushed with cold water, also by successively introducing into the tubes a quantity of hot steam followed by a quantity of cold water, or vice versa. The elongation or shortening of the tubes thus produced will cause a distortion of the unequal length U-tubes and a distinct warping of the curved members as above described.

Because of the fact that the tube bundle 20 is constructed in sections, as previously described, it can be readily removed from the evaporator shell. Thus it is a simple matter to take off the shell cover and then take out the tube bundle sections one at a time.

By means of my present invention, the necessity of providing tube sheets at both ends of the tube bundle is eliminated, moreover the tube sheets 29 and 30 are both at the same end of the tube bundle and can be readily maintained in fixed relation one to another because of their proximity and because of the fact that they can be readily made as a unitary structure, such, for example as the headers 31.

It will be understood that the legs of the tubes may be perfectly straight or that they may be slightly bowed, and the term straight as used in the appended claims is intended to include either construction.

The foregoing description of my invention in connection with the accompanying drawings, is to be considered as an exemplifying disclosure and the invention extends to those forms of construction which come within the terms of the appended claims, for instance, the manifolds might be turned 90° to the positions shown in the drawings, in which event all portions of each tube would lie in substantially the same horizontal plane. Furthermore, referring to Fig. 5, there may be a greater number of straight and curved portions than indicated and the longs and shorts need not be uniform, but may be varied if alternate lengths are different, so that the developed tube may conform to the contour of the containing shell of the evaporator.

I claim:

1. In a heat exchanger, a tube comprising a plurality of straight portions and at least one curved portion, each straight portion being serially joined through the medium of a curved portion of flattened cross section with at least one other straight portion of substantially different length, and means for

- fixedly mounting each end of said tube, prising a plurality of serially joined portions of different length with the ends of the tube contiguous with portions of substantially different length, said tube comprising at least one pair of joined portions of different lengths constituting an assemblage in which the longer portion has an over-change of length due to temperature variations, greater than that of the other portion, and means for preventing relative displacement of the ends of said tube whereby the tubing of which said longer portion is composed is caused to warp in response to temperature variations, thus facilitating the breaking up of scale formations thereon. 70
2. In a heat exchanger, a U-shaped tube having legs of substantially different lengths and means for preventing relative displacement of the ends of the tube whereby variations in the lengths of said legs resulting from temperature changes cause warping of the tube and thus facilitate the breaking up of scale-formations thereon. 75
3. In a heat exchanger, a plurality of U-shaped tubes having legs of unequal length, and a header having tube receiving surfaces displaced from one another in a direction longitudinally of the tubes and in relatively fixed positions, one end of each leg of said U-tubes being secured in each of said tube receiving surfaces. 80
4. In a heat exchanger, a header having tube receiving surfaces in different planes and in relative fixed positions, and U-shaped tubes having legs of unequal length, one end of each leg being secured in each of said tube receiving surfaces. 85
5. In a heat exchanger, a tube of serpentine form comprising a plurality of substantially parallel straight portions joined together by return bends, and characterized by having no two consecutive straight portions of substantially the same length, whereby the differences in lengthwise contraction and expansion of the consecutive straight portions causes a deformation of the serpentine tube and exerts a scale-shedding action upon the formations thereon. 90
6. In a heat exchanger, a tube comprising a plurality of serially joined portions of different length with the ends of the tube contiguous with portions of substantially different length, and means for preventing relative displacement of the ends of said tube whereby the difference in deformation between adjacent portions of different length resulting from temperature variations causes a flexing of the tube which aids in removing scale therefrom. 95
7. In a heat exchanger, a tube comprising a plurality of serially joined straight portions with the ends of the tube contiguous with portions of substantially different length, and means for preventing relative displacement of the ends of the tube whereby the difference in lengthwise contraction and expansion between the adjoining straight portions of different length causes said straight portion to flex and thus exert a scale-shedding action upon scale formations thereon. 100
8. In a heat exchanger, a bent tube com-
